UNITED STATES PATENT OFFICE.

EDWIN C. FELLOWS, OF PHILADELPHIA, PENNSYLVANIA, ASSIGNOR TO
THE ENTERPRISE MANUFACTURING COMPANY OF PENNSYLVANIA, OF
PHILADELPHIA, PENNSYLVANIA, A CORPORATION OF PENNSYLVANIA.

ELECTRIC CONTROLLER.

No. 839,742.

Specification of Letters Patent.

Patented Dec. 25, 1906.

Application filed June 1, 1906. Serial No. 319,741.

To all whom it may concern:

Be it known that I, EDWIN C. FELLOWS, a citizen of the United States, residing in Philadelphia, Pennsylvania, have invented 5 certain Improvements in Electric Controllers, of which the following is a specification.

One object of my invention is to provide certain improvements in the detail construction of controllers particularly designed for 10 starting and regulating the speed of electric motors; and with this object in view I desire to provide a contact-finger and auxiliary contacts so placed that whatever arc occurs on making or breaking the field and armature circuits will be necessarily confined to 15 said contacts.

I further desire to so construct and mount the stops for the controller-handle or contact-arm that there shall be no tendency for 20 this to break the slate or marble of the controller-face, even though it be brought into violent contact with said stops.

Another object of my invention is to provide an improved form of adjustable bearing 25 for the contact-arm, as well as contact-brushes of improved construction designed to be mounted on said arm. I also desire to so arrange the contacts and connections of my controller that a body of resistance, prefer- 30 ably that used to regulate the field-current, will be placed in series with the motor field-winding just prior to breaking the field-circuit, thereby cutting down and preventing damage from the induced field-current.

These objects I attain as hereinafter set 35 forth, reference being had to the accompanying drawings, in which—

Figure 1 is a front elevation of a controller constructed according to my invention. Fig. 40 2 is a rear elevation of the controller illustrated in Fig. 1. Fig. 3 is a vertical section of the controller, taken through one of the auxiliary contacts and the contact-brushes of the contact-arm. Fig. 4 is a side elevation 45 of the contact-arm. Fig. 5 is a side elevation of the bearing-piece for the contact-arm, showing the stops thereon; and Fig. 6 is a diagrammatic view illustrating the electrical connections of my improved controller 50 and the connections between it and an electric motor.

In the above drawings, A is a cast-iron frame or skeleton casing, in which are mount-

ed any desired number of bodies of resistance B—in the present instance in the form of a single coil of flat section. On the front of the frame A is mounted a plate or slab C of slate, marble, or other desired insulating material, and this carries a pair of terminals c and c' for the attachment of field and armature 55 conductors, respectively. Also mounted on the plate C is a bearing-piece c², consisting of a flat body portion and a bearing portion c³, projecting from both sides thereof. In addition at both ends of said body portion are 60 upwardly-extending lugs c⁴, of which one has a projection v⁵ serving as a terminal for the 65 attachment of one of the line conductors. 70

One part of the bearing portion c³ extends through the plate C, while to the other part 75 is fitted the boss of a contact-arm D. It will be seen that the thickness of this boss is slightly greater than the length of the part on which it is mounted and that it is held in position by means of a screw-bolt d, which 75 passes through said part c³. This bolt is provided with a nut and washer and has in addition between the boss of the arm D and its head a fiber washer d' and, if desired, a metal washer d² for a purpose hereinafter 80 noted.

The arm D consists of a straight body portion extending radially from the boss and provided at its end with two branches d³ and d⁴, of which the first is provided with a handle 85 d⁵, while on the second branch is a piece d⁶, designed to serve as a contact-finger. Said piece is pivotally mounted on a screw d⁷ and is normally held in a definite position by means of a double-acting spring d⁸, the ends 90 of which are extended substantially parallel to each other, so as to engage between them two pins d⁹ and d¹⁰, the first of which projects from the branch d⁴ of the contact-arm D, while the second projects from the contact-finger. The body-section of the said arm D has two upwardly-projecting tubular lugs 95 d¹¹ and d¹² open on their bottom faces only, and containing springs d¹³ and contact-brushes d¹⁴ and d¹⁵, respectively. 100

Mounted in the arc of a circle upon the plate C and concentric with the bearing portion of the piece c² is a series of contact-buttons e, while upon the arc of a second circle, also concentric with the said bearing portion, 105 are two elongated contact-pieces e' and e'.

There are also two auxiliary contacts e^3 and e^4 , mounted on the plate C, beyond the contact-piece e' , in such position as to bear a definite relation to this and to others of the contact-buttons mounted upon the plate C. Said auxiliary contacts preferably consist of tubular pieces held in position by screws, as shown in Fig. 3, each having an adjustable and removable rod e^5 , held in place by a set-
10 screw e^6 .

When in use, the various parts of the controller are connected, as shown in Fig. 6, one of the supply-mains f being connected to the contact-arm at the terminal c^5 , while one of the terminals c of the plate C is connected to one end of the motor-field g , whose opposite end is connected to the second supply-main f' . The motor-armature g' has one terminal also connected to the supply-main f' and its second terminal connected to the terminal c' on the plate C, which latter terminal is also connected to the contact strip or button e^2 .

It will be seen from an inspection of the drawings that the contact-strip and the first two of the contact-buttons e are dead—i. e., they are at no time included in the electric circuit, but serve to maintain the spring-pressed brushes d^{13} and d^{14} at the proper level when these are not in engagement with the live members of the controller-contacts. The resistance B is connected at different points to the various contact-buttons e , while the last of these buttons is connected to the auxiliary contact e^3 , the second auxiliary contact e^4 being also connected to the contact-strip e^2 . The terminal c is connected to one of the contact-buttons e and also to the end of the resistance B.

When the contact-arm D is moved to the extreme left of its path of motion, it will be seen that it engages one of the stops c^4 and that its brushes engage the dead contact-strip e' and one of the dead contact-buttons e . As, however, said handle is moved to the right in order to start the motor the contact-finger d^5 first engages the rod e^5 of the auxiliary contact e^3 , so that the field-circuit of the motor is completed from the supply-main f' through the field-winding to the terminal c , through all the resistance B, auxiliary contact e^3 , contact-arm D, and terminal c^5 to the supply-main f . By this means any arcing which occurs when the field-circuit is completed takes place on the rod e^5 .

As the arm D is moved farther to the right its brush d^{13} engages the first one of the live contact-buttons e , thereby short-circuiting the resistance B, so that the field-current is now free to pass from the field-winding through the first contact-button, thence through the arm D directly to the terminal c^5 and the second supply-main f . Continued motion of the arm D toward the right displaces the contact-finger d^5 from its normal position, turning it on its pivot against the

action of the spring d^7 , until finally such motion has proceeded far enough to permit said finger to become quickly disengaged from the rod e^5 and be returned to its normal position by said spring. Further movement of the contact-arm D to the right next brings the contact-finger into contact with the second one of the auxiliary contacts e^4 , thus completing the armature-circuit of the motor from the supply-main f' , through the armature g , terminal c' , contact-strip e^2 , auxiliary contact e^4 , arm D, terminal c^5 , and supply-main.

If the motor is of the shunt-wound type, as in the case illustrated, it will now start and run at its slowest speed, it being noted that any arc formed by the completion of the armature-circuit occurs on the rod of the auxiliary contact e^4 .

As the contact-arm is further moved the two brushes d^{13} and d^{14} are respectively brought into engagement with the second live contact-button e and with the contact-strip e^2 , after which the finger d^5 is quickly disengaged from the rod of the second auxiliary contact e^4 under the action of the spring d^7 , as in the case of the auxiliary contact e^3 . By movement of the contact-arm to its full "on" position the resistance B is gradually cut into the field-circuit, thereby weakening the field of the motor and causing said motor to speed up in the well-known manner. No matter how violently the arm D may be brought into contact with either of the stops c^4 there is no tendency to crack or break the marble or slate plate C, as has been the case with stops mounted on the face of controllers heretofore made, the reason for this being that the effect of such a blow or strain in the present instance is taken by the metallic casting c^2 and is not transmitted through the slate or marble from the stop to the pivot of the said contact-arm.

When the contact-arm is moved from its full "on" toward its "off" position, the resistance B is cut out of the field-circuit by a number of steps, and just before brush d^{14} moves off the contact-strip e^2 the finger d^5 comes into engagement with the rod e^5 of the auxiliary contact e^3 . As a consequence the said brush may be moved completely off of the contact-strip e^2 without breaking the armature-circuit, which is still completed through the contact-finger and the auxiliary contact e^4 . Finally, however, the finger is drawn past the rod e^5 and under the action of the spring d^7 is quickly moved out of contact therewith, so that it breaks the armature-circuit and causes any arc which may be formed to occur between said finger and rod. Similarly, before the brush d^{13} leaves the last one of the live contact-buttons e the finger d^5 engages with the rod of the auxiliary contact e^3 , so that when said brush d^{13} finally passes off this last live-contact button the

field-current is reduced by being made to pass through the resistance B. As a result when said current is finally broken by the finger moving out of engagement with the auxiliary contact e^3 the resistance B so far cuts down the current induced by the breakage of the field-circuit that all danger of puncture of the field insulation is effectually avoided. Furthermore, any arc occurring is necessarily limited to the auxiliary contacts, and when from continued use the contact-arm becomes loose on its supporting-pivot the wear may be quickly taken up and the arm tightened by properly setting up the screw-bolt d , the fiber washer d' allowing of said setting up without causing undue binding between the parts. It will be further noticed that the portion of the bearing, c^3 which extends into the slate is internally threaded, so that the arm D is held in position and may be adjusted independently of the nut on the washer whereby the piece e^2 is held to the plate C.

By the arrangement of the tubular projections d^{10} and d^{11} with their springs and brushes d^{13} and d^{14} the uniform pressure of these latter on the contact-buttons and strips is assured without the need of adjusting means or confining devices, which are likely to get out of order or require constant attention. Should the contact-rods e^5 at any time become burned or pitted, it is a comparatively easy matter to loosen the set-screws e^6 , and so turn said rods as to present fresh surfaces for engagement with the contact-finger d^5 .

I claim—

1. The combination of a supporting-plate, a series of contact-buttons thereon, an auxiliary contact, a contact-arm pivotally mounted on the plate having a contact-brush placed to engage said contact-buttons, and a contact-finger carried by the arm so as to remain in engagement with said auxiliary contact until after said brush has become disengaged from the first contact-button when the arm is moved in either direction, substantially as described.

2. The combination of a supporting-plate, a series of contact-buttons thereon, an auxiliary contact, a contact-arm pivotally mounted on the plate having a contact-brush placed to engage said contact-buttons, and a contact-finger carried by the arm so as to remain in engagement with said auxiliary contact until after said brush has become disengaged from the first contact-button when the arm is moved in either direction, with a spring for normally retaining said arm in a definite position, substantially as described.

3. The combination in an electric controller, of a supporting-plate, an arm having a pair of contact-brushes thereon, contact-buttons on the plate placed to be engaged by said contact-brushes, with a plurality of aux-

iliary contacts on the plate, and a contact-finger on the arm placed to coöperate with said auxiliary contacts, said finger being placed to engage said auxiliary contacts before said contact button or buttons are engaged by the brushes when the arm is moved in one direction, and to remain in engagement with said auxiliary contacts after said contact-brushes have been disengaged from said contact or contacts when said arm is moved in the opposite direction, substantially as described.

4. The combination in an electric controller, of a plate of insulating material, a series of contacts thereon, a metallic structure mounted on the plate, an arm pivotally mounted on said structure for coöperation with the contacts, with a stop or stops carried by the metallic structure for limiting the movement of the arm, substantially as described.

5. The combination in an electric controller, of a plate of insulating material, a series of contacts thereon, a metallic structure mounted on the plate, an arm pivotally mounted on said structure for coöperation with the contacts, with a stop on each side of said metallic structure for limiting the movement of said arm, substantially as described.

6. The combination in an electric controller, of a plate of insulating material, a series of contacts thereon, a metallic structure mounted on the plate and having a terminal, an arm pivotally mounted on said structure for coöperation with the contacts, and a stop on each side of the metallic structure for limiting the movement of said arm, substantially as described.

7. The combination of a plate of insulating material, a series of contacts mounted thereon, a metallic piece having an upwardly-projecting lug or lugs, with an arm pivotally mounted on said piece for coöperation with said contacts, said lugs serving as stops for limiting movement of the arm, substantially as described.

8. The combination with a plate of insulating material, of contacts thereon, a metallic piece mounted on said plate having an upwardly-projecting pivot, an arm coöperating with the contacts and mounted on said pivot, said arm being of greater thickness than the length of said pivot, with a bolt extending into the pivot and having a washer of relatively soft material between its head and said arm, substantially as described.

9. The combination of a plate of insulating material, contacts thereon, an arm coöperating with said contacts and provided with a boss, a metallic piece mounted on said plate having a projecting pivot extending into the boss of the arm, a bolt passing through the pivot portion of said piece and threaded into the same, with a nut on said bolt for holding

the piece to the plate, and a washer of relatively soft material between the head of the bolt and the boss on the arm, substantially as described.

5 10. An electric controller having a contact button or buttons, a body of field resistance connected to said buttons, an auxiliary contact, a structure having a contact brush or brushes for engagement with said contact-
10 buttons, and also having a contact-finger for engagement with the auxiliary contacts and connections between the contact-buttons and the auxiliary contact so arranged that the re-
15 sistance is placed in series with the field of a motor connected to the controller before the field-circuit is broken when the movable structure is operated to its "off" position, substantially as described.

11. The combination in an electric con-
20 troller of a series of contact-buttons, a body of resistance connected thereto, an auxiliary contact, a contact-arm carrying a brush capable of engagement with said contact-buttons, an auxiliary contact connected to the buttons, 25 and a spring-controlled finger on the contact-arm, the parts being arranged so that the body of resistance is connected in series with the field of the motor when the field-circuit is finally broken on the auxiliary contact, as the 30 arm is moved to its "off" position, substantially as described.

12. The combination in an electric controller of a plate of insulating material, a series of contact-buttons thereon, a body of field 35 resistance connected to said contact-buttons,

an auxiliary contact also connected to the buttons, a contact-arm having a brush coöperating with the contact-buttons, and a spring-actuated finger placed to coöperate with the auxiliary contact, said parts being 40 so arranged and connected that said resistance is cut into the circuit of the field of the motor as the contact-arm is moved in one direction, and is cut out of said circuit as the contact-arm is moved in another direction, 45 being finally placed in series with the motor-field and the auxiliary contact, substantially as described.

13. The combination in an electric controller of two series of contact-buttons, one connected to the armature of an electric motor, and the other to the field of such motor, a body of resistance connected to one of said series of contact-buttons, an auxiliary contact for each series of buttons, and a contact-
50 arm having brushes placed to engage said two series of contact-buttons, there being a spring-controlled contact-finger mounted on said contact-arm and placed to engage said auxiliary contacts at certain predetermined 55 points in the path of motion of the arm, substantially as described.

In testimony whereof I have signed my name to this specification in the presence of two subscribing witnesses.

EDWIN C. FELLOWS.
